UNITED STATES PATENT OFFICE

2,363,853

ELECTRIC AIR CIRCUIT BREAKER

Robert M. Bennett, Ithaca, Pa., assignor to General Electric Company, a corporation of New York

Application June 5, 1942, Serial No. 445,857

4 Claims. (Cl. 200—145)

My invention relates to electric air circuit breakers, more particularly to air circuit breakers for interrupting moderate voltage power circuits under all current interrupting conditions including the interruption of both low amperage and short circuit current arcs.

The interruption of high amperage moderate voltage power arcs by air circuit breakers of the magnetic blowout type rated at from 5000 to 7500 volts for example, has been successfully accomplished and such circuit breakers have been put into extensive commercial use. These breakers can also be made to interrupt light currents at 15 kv. but at heavier currents are less satisfactory. Although various methods have been proposed for enabling the circuit breaker to interrupt both high and low current arcs, such as for example applying an auxiliary fluid jet for interrupting arcs in the low current range, the problem of interrupting such low amperage arcs within a cycle or two of arcing presents itself from the practical standpoint whenever a new design of high current interrupting capacity breaker is developed. This is due to the fact that the circuit breaker characteristics favoring the interruption of high or short circuit current arcs do not always favor the interruption of low current arcs, so that a low current arc may "hang on" for an excessively long arcing time before it is finally extinguished.

A principal object of my invention therefore is the provision of an improved air circuit breaker that is capable of efficiently interrupting large overload and short circuit currents as well as extinguishing low amperage arcs and arcs of intermediate current values, all within a very brief arcing time.

In accordance with my invention, radically different circuit breaker characteristics are combined in such a manner that an effective and efficient arc extinguishing agency is applied for interrupting the power arc regardless of its current magnitude. I accomplish this by using a resistance method of arc interruption wherein the arc is greatly lengthened and attenuated as it is forced into contact with cooling surfaces of large area, and a so-called expulsion method wherein interrupting gas is liberated by the arc heat from insulating structure closely adjacent or in confining relation to the arc and caused to flow through the arc stream. The volume of such gas liberated is proportional to the magnitude of the arc current.

My invention will be more fully set forth in the following description referring to the accom-

panying drawing, and the features of novelty which characterize my invention will be pointed out with particularity in the claims annexed to and forming a part of this specification.

- 5 Referring to the drawing, Fig. 1 is an elevational view, partly in section of an air circuit breaker of the double-break type embodying my invention and Fig. 2 is a sectional view taken along the line 2—2 of Fig. 1.
- 10 The air circuit breaker illustrated by Fig. 1 is shown for example in a form that is particularly adaptable for central stations and substations wherein the circuit breaker unit can be bodily connected and disconnected with respect
- 15 to the stationary circuits by a simple plugging operation. In the present instance, the circuit breaker is of the well-known drop-down type wherein disconnection is effected merely by bodily lowering of the circuit breaker after the
- 20 breaker has been opened. The breaker unit, including its supporting frame indicated at 1, is usually housed in a grounded metal enclosure or cubicle (not shown). The relatively movable contact structure of the breaker comprises a
- 25 pair of fixed contacts at 2 and 3 and a relatively movable coacting bridging contact 4 that is operated by means of a reciprocally movable insulating rod 5. The operating rod 5 is suitably connected to an actuating mechanism (not
- 30 shown) carried by the frame 1 so that upon lowering of the bridging contact two breaks in series are formed in the power circuit. The fixed contacts 2 and 3 are electrically connected to the lower ends of the lead-in conductor studs 6
- 35 and 7 respectively which also serve as plug type disconnecting contacts for the breaker unit. When the breaker is connected in a power circuit, lowering of the bridge contacts 4 to open the circuit may cause an arc to form at each
- 40 break. It will be apparent that the two series breaks may be formed either simultaneously or in timed sequence as desired.

45 In order to extinguish the arcs so formed at the series breaks 2—4 and 3—4 under all arcing conditions including low and very high amperage arcs, I provide at the break 2—4 an arc chute 8 of the interference-barrier type for example, and at the break 3—4 an arc chute 9 of the expulsion type. The arc drawn at the arc chute 8 is subjected to intensive cooling and attenuation so that the resistance of the arc stream is greatly increased, and the arc at the chute 9 is subjected to the expulsion effect of suddenly liberated arc-extinguishing gas, the amount 50 of the gas liberated depending on the arc

heat and consequently the arc current magnitude. By subjecting the two portions of the interrupting arc to these fundamentally different arc extinguishing methods, I provide means for always applying, at least to one arc, an efficient and positive arc extinguishing agency regardless of the magnitude of the arc current.

The arc extinguishing structure generally indicated at 8 is mounted with respect to the separable contacts at 2-4 so as directly to receive the power arc which is under the influence of a magnetic blowout force, such as produced by blowout coils 10 and 11 in a manner similar to the conventional arc chute wherein the arc is formed at the entrance of the chute and is rapidly extended in the form of a loop through the chute toward the exhaust opening at the opposite end thereof. Certain features of this extinguishing structure are disclosed and claimed in Letters Patent No. 2,293,513, issued August 18, 1942 to L. J. Linde.

Referring now to both Figs. 1 and 2, the arc chute 8 comprises spaced side walls 12 and 13 composed of arc resisting material, preferably of inorganic insulating material such as an asbestos compound, each side wall having on the side facing the other wall a plurality of parallel ridges or fins 12' and 13' respectively. The fins 12' and 13' extend longitudinally from the chute entrance to the chute exhaust and are preferably integral with the side walls which are joined and suitably clamped together at the ends 14 and 15 so as to form an arc chute. The length and spacing of the fins 12' and 13' are preferably such that when the side walls 12 and 13 are clamped together, the fins of one wall are staggered or interleaved with respect to those of the other, so as to form a restricted sinuous or tortuous passage 16 into which the arc is driven at the entrance 17 of the arc chute. As shown by Fig. 1 which illustrates in partial detail but half the extinguishing structure, namely the inner side wall 12, the fins project inwardly in a direction transverse to the direction of the movement of the arc as it passes from the entrance 17 into and through the chute. At the exhaust end of the chute suitable gas cooling structure 17' is disposed.

As the arc is driven by the magnetic blowout field into the entrance passage 17, there is comparatively little transverse deflection of the arc stream during this initial movement due to the fact that the fins 12' and 13' are tapered toward the arc entrance. As the arc is driven into the zigzag space defined by the interleaving fins, the cross-section of the arc is reduced as the arc assumes a serpentine form. If the arc is not interrupted in this region, the blowout field continues to move the arc outward through the arc passage toward the exhaust thereby progressively lengthening the path of the arc as the amplitude of the zigzag path becomes greater. The arc is thereby greatly lengthened and attenuated concurrent with great cooling effect due to the large cooling surface of the fins engaged by the arc during its approach to the exhaust arc of the chute. This cooling of the lengthened and attenuated arc stream so increases its electrical resistance that the arc current is correspondingly reduced together with improvement of the power factor. Accordingly, the interrupting operation at a current zero is greatly facilitated and is not accompanied by system disturbance.

The specific blowout arrangement includes a pair of magnetic blowout coils 10 which are electrically connected to the conductor stud 6 and to the arc runners 10' so that the arc current serially traverses the blowout coils after separation of the contacts in a manner well-known in the art. Normally the current is carried in the closed circuit position of the breaker by the spring-biased contact 2a which engages the contact portion 4a of the bridge, the current being shunted first to the transfer contacts 2b and 4b and then to the arcing contacts 2c and 4c as the breaker opens. After the arc is drawn at the break 2-4 and when it reaches an extended position its lower root transfers to the arc runner 11', so that the blowout coil 11, one terminal of which is electrically connected through the flexible conductor 18 to the bridge 4 and the other to the runner 11', also is connected in series in the interrupting circuit. Accordingly, as the arc proceeds into the chute all the blowout coils become energized by the arc current to establish a magnetic blowout field which passes transversely across the chute between the usual pole plates (not shown) and drives the arc towards the chute exhaust according to well-known principles.

When very low values of current are to be interrupted the magnetic forces generated by the blowout coils are insufficient rapidly to move the arc through the arc passages toward the exhaust end. For this purpose a "puffer" comprising a cylinder 4d and a piston 4e is provided. The piston is suitably connected to the bridging contact 30 by the hollow piston rod 4f which also serves as a nozzle for directing a jet of air across the arc. Opening movement of the bridging contact 4 drives the piston 4e down in the cylinder 4d thereby forcing the air trapped below the piston to flow out through the tube 4f across the arcing contacts in a direction to drive the arc into the arc passages.

This type of arc extinguishing device is very effective in interrupting low or moderate amperage arcs. Such arcs are not excessively "fat" and therefore can be driven by the blowout field into the restricted passage formed by the closely spaced interleaving fins or barriers. Also the magnetic blowout field is not so great that the arc is driven through the chute before it has had sufficient cooling contact with the chute passage walls. Within this passage the arc is greatly lengthened and squeezed between the chute side walls thereby facilitating heat transfer from the arc stream so that the arc current is rapidly decreased by the increased resistance of the arc stream. This greatly reduced arc current, together with a power factor approaching unity makes final extinction of the arc at a current zero comparatively simple.

The arc chute 9 at the break 3-4 is of the expulsion type and is particularly adapted to handle considerably higher amperage arcs. The arc is formed between the finger contacts 3' secured to the fixed contact 3 and a blade-like member 4' connected to one end of the bridge 4 so that when the bridge is lowered an arc is formed in a slot-like passage 19 formed at the entrance part of the chute 9. The chute 9 comprises a pair of spaced insulating side walls composed of fiber or the like, one of which is indicated at 20, and co-operating end walls 21 and 22 of similar material arranged to form a narrow diverging arc chute, the exhaust end of which communicates with an

arc gas venting conduit 22. A plurality of insulating barriers 23 form partitions in the chute so that arc gases formed in the passage 19 flow to the venting tube 22 through separate passages 23'. The converging edges of the barriers 23 are spaced adjacent to the contact blade 4' so that the power arc is drawn across the openings of the exhaust passages 23' in succession. Metallic cooling plates 24 are interposed in the passages 23' for reducing the temperature of the exhaust gases. The insulating barrier 25 extends across the passage 19 and is provided with a slot in registry with the blade 4' for confining the arc flame within the chute at the movable contact.

For the purpose of interrupting the arc formed within the passage 19, the insulating barriers 23, particularly at their converging edges, as well as the side walls of the passage 19, are composed of a material, preferably an organic material such as hard fibre or urea resin, that is capable of producing under influence of the arc heat an appreciable volume of arc extinguishing gas. The quantity of gas liberated depends upon the intensity of the arc heat at the insulating surface of the barriers and side walls, and in the case of large short circuit currents a considerable amount of interrupting gas is liberated so suddenly as to produce an explosive-like force tending to blow out the arc. This explosive-like force tends to expel the arc into the arc chute where it is stretched between the converging edges of the barrier 23 and extinguished. My invention, it should be noted, is not limited to a specific form of expulsion-type breaker at 9 and comprehends any suitable type wherein the production of arc extinguishing gas is increased in accordance with arc current values.

It will therefore be apparent that I have provided a double-break air circuit breaker with means for interrupting moderate voltage power currents within a wide range of interrupting conditions. Although I have shown by way of example a double-break circuit breaker, it shall be understood that it is within the scope of my invention to employ a single-break breaker wherein the arc is drawn, for example, first through the expulsion chute 9, and then through the resistance chute 8 for finally interrupting low amperage arcs that are not extinguished by expulsion action within the chute 9. Also, the bridge contact 4 may readily be designed so that any desired sequence of contact separation can be obtained.

It should be understood that my invention is not limited to specific details of construction and arrangement thereof herein illustrated, and that changes and modifications may occur to one skilled in the art without departing from the spirit of my invention.

What I claim as new and desire to secure by Letters Patent of the United States is:

1. An air circuit breaker comprising relatively movable contacts arranged to draw the interrupting arc substantially simultaneously within two arc extinguishing structures, one of said structures having arc barriers composed of an inorganic insulating material arranged to lengthen and attenuate the arc as it passes into said structure so as to cool the arc stream and greatly increase its electrical resistance, the other of said extinguishing structures forming a pas-

sage in part closely confining a portion of said interrupting arc, said passage having walls and confining structure composed of organic insulating material, such as hard fibre, adapted to release an arc extinguishing gas under influence of the arc heat, said last-named extinguishing structure having means for directing said gas through said arc portion to extinguish it by explosive action.

10 2. An air circuit breaker comprising relatively movable contacts arranged to draw the interrupting arc substantially simultaneously within two arc extinguishing structures within which the interrupting arc is formed upon separation of said contacts, one of said structures comprising an arc chute having magnetic blow-out means and inorganic insulating arc barriers arranged to lengthen and attenuate the arc as it is driven by the blowout field into said structure so as to cool the arc stream and greatly increase its electrical resistance, the other of said extinguishing structures also comprising an arc chute forming a passage in which a portion of the interrupting arc is drawn, said passage having walls in part surrounding said arc portion composed of insulating material adapted to release an appreciable volume of arc extinguishing gas under influence of the arc heat, said last-named arc chute having venting means for directing said gas so as to extinguish said arc portion by explosive action.

15 3. An air circuit breaker comprising relatively movable contacts arranged to draw two interrupting arcs in series, an arc chute in which one of said arcs is drawn having magnetic blowout coils and interleaving arc barriers composed of an inorganic insulating material arranged to lengthen and attenuate the arc as it is driven by the blowout field into said chute so as to cool the arc stream and greatly increase its electrical resistance, a second arc chute in which the other of said arcs is drawn for confining said arc, said second chute having structure including spaced barriers in intimate relation to said arc composed of organic insulating material, such as hard fibre, adapted to release an appreciable volume of arc extinguishing gas under influence of the arc heat, said last-named arc chute having a plurality of venting passages for directing said gas so as to extinguish said arc portion by explosive action.

4. An air circuit interrupter comprising arcing means for the interrupting arc, an arc extinguishing chamber in which one part of said arc may form having closely confining walls of organic insulating material adapted to release an arc extinguishing gas under influence of the arc heat and means for directing said gas from said chamber through the arc to extinguish it by explosive action, and a second arc extinguishing chamber in which another part of said arc may form substantially simultaneously with said one part of said arc having closely confining walls of inorganic insulating material, said inorganic insulating walls being in good heat transfer relation to the arc stream and being arranged to lengthen and attenuate the arc stream thereby to cool the arc and greatly increase its electrical resistance.

ROBERT M. BENNETT.
